UNITED STATES PATENT OFFICE

WILLIAM BLANCHARD, OF WAKEFIELD, MASSACHUSETTS

SHADE MOUNTING

Application filed January 6, 1930. Serial No. 418,872.

My invention relates to improvements in shades and carriers therefor,—having particular reference to devices of this kind for the horizontally pivoted windows of factories 5 although capable of other uses.

Briefly stated, the invention has for one of its primary objects the provision of a novel shade mounting whereby efficient light control will be had without interfering with ventilation,—particularly where the window has a horizontally pivoted sash.

Another object of the invention is to provide a shade mounting associated with a window sash whereby the shades and sash may 15 be easily operated,—and which will eliminate the necessity for guide rods, special shade brackets and the like.

A further object of the invention is to provide a shade mounting which can be readily applied to window sash, and which incorporates novel carrier means having a portion adapted to intercept and prevent the passage 20 of light between adjacent shade rolls.

A still further object of the invention is to 25 provide in a shade carrier, means for limiting the movement thereof and protecting the window sash, shade carrier and shades against injury in the event that the window is carelessly opened.

The invention also resides in certain novel 30 features of construction, combination and arrangement of the various parts, and in modes of operation,—all of which will be readily apparent to those skilled in the art upon reference to the accompanying drawings in connection 35 with the following detailed description disclosing what now appears to be a preferred mechanical expression of the invention. It is to be understood of course that the disclosure herein is susceptible of considerable 40 change and modification within the spirit and scope of the subject matter claimed herein-after.

In the drawings, 45 Figure 1 is an elevational view taken from the inside of a building and illustrating the application of my invention to a window having a horizontally pivoted sash section;

Figure 2 is a vertical sectional view through 50 a window frame and illustrating my inven-

tion in side elevation with the swingable window sash closed;

Figure 3 is a cross sectional view through a window frame and showing my invention in top plan;

Figure 4 is a view similar to Figure 2 but showing the sash swung open;

Figure 5 is a detail top plan view partly in section and showing the application of my special carrier to the swingable sash, the shade roll being removed;

Figure 6 is a fragmentary and elevational view showing the upper end of the swingable sash and my carrier applied;

Figure 7 is a detail view partly broken and partly in section showing a snubber element.

Referring specifically to the drawings, wherein the same reference characters designate the same parts throughout the several views, numeral 1 denotes a window frame having a horizontally pivoted sash 2 provided with pintles 2^a and carrying at its upper end a pair of spaced angle brackets 3, secured as at 4 and serving as a support for the horizontal portion of a carrier plate 5 which is T-shaped in cross section. The carrier plate 5 has a head portion extending laterally toward each side as indicated at 5^a in Figure 6. The carrier plate 5 is provided at each end with slots 6^b adapted to receive the bolts 6^a which clamp the plate to the brackets 3 and also extend through the base portions of the shade carrier bearings 6, the roller shades being designated at 7, 7^a. Figures 2 and 4 clearly illustrate that a line 8 is secured to the upper shade 7 and passed through a guide 9 at the top of the window opening from whence it is brought down and passed through the guide 10 of the window sill 11 from which it is led upwardly and connected to the shade 7^a.

It is believed to be plain that the two shades 7, 7^a can be readily operated by means of the single line 8 whether the sash 2 is closed as in Figure 2 or open as in Figure 4. The shades will be clear of the sash and the head portion 5^a of plate 5 effectually prevents the passage of light through the space between the rolls 7, 7^a. Furthermore, the T-shaped cross sectional formation of carrier member

5 gives same great strength and rigidity enabling it to be used for window sash of great width.

Figures 1 and 4 show that bracket members 12 are secured to each side of the window frame as at 12^a and are provided with offset threaded sockets 13 receiving the tapped end of a sleeve-like guide member 14 having therein a coil spring 15 whose lower end is anchored to the transverse cotter pin 15^a. The upper end of the frame 15 is connected to the chain or other flexible connection 16 which is passed over the pulley 17 carried by the window frame and finally connected, as indicated in Figure 5, to the end of the carrier member 5. Figure 1 clearly illustrates that one of the snubber units just described is at each side of the window. It will be plain that upon release of the window the flexible connections 16 with the springs 15 in carriers 14 will prevent the window from jarring out and abruptly stopping to thereby prevent injury to the shades or windows.

It will also be clear that the sash may be 25 swung about seventy degrees from the position shown in Figure 4 so that the upper end of the sash will be directed toward the floor,—the springs yielding to permit this movement and maintaining the sash in the new position since the carrier will be thrown past dead center and the action of connections 16 will tend to direct and hold the sash inward.

Having thus described my invention what I claim as new and desire to secure by Letters 35 Patent is:

1. The combination of a shade carrier, means for attaching said carrier to a swingable sash, roller shades having bearing brackets secured to opposite faces of said carrier with their axes in a plane substantially parallel to said sash, a combined strengthening and light-intercepting head formed at one edge of said carrier in front of the shade rolls, a flexible connection having guide means at the 45 top and bottom of the window frame and connected to said shades for operating the same, and snubber means connected to said carrier member and adapted to be connected to the window frame.

50 2. In a horizontally pivoted window sash and double hung shade construction,—the combination of a shade carrier, means for attaching said carrier to a swingable sash, roller shades having bearing brackets secured to 55 opposite faces of said carrier with their axes in a plane substantially parallel to said sash, a combined strengthening and light-intercepting head formed at one edge of said carrier in front of the shade rolls, and a flexible 60 connection having guide means at the top and bottom of the window frame and adapted to be connected to said shades for operating the same.

65 3. The combination set forth in claim 2 and including a flexible connection secured to

said carrier at one end and to a yieldable element at the other end, a guide housing receiving said yieldable elements and adapted for attachment to the window frame.

4. The combination set forth in claim 2, 70 and means for adjustably mounting said bearing brackets upon said carrier.

5. In a device of the class described an elongated carrier member of T-shaped cross section, angle brackets adapted to engage the stem flange of said carrier member for securing the same to a window sash, shade roller brackets carried by opposite faces of said stem flange of said carrier member, shade rolls carried in said brackets in a plane inwardly of and parallel with the front edge of the sash,—the head portion of said T-shaped carrier member being disposed in advance of said roll and closing the space between the same, and control means for said shade rolls. 75 80 85

6. The combination set forth in claim 5 and snubber means connected to said carrier member and having a portion adapted for connection to a window frame. 90

7. In a device of the character described, a shade carrier, means for attaching said carrier to a swingable sash, roller shades having bearing brackets secured to opposite faces of said carrier, means for operating said roller shades, and snubber means connected to said carrier member and adapted to be connected to the window frame. 95

8. In a device of the character described, a shade carrier, means for attaching said carrier to a swingable sash, roller shades having bearing brackets secured to opposite faces of said carrier, a flexible connection having guide means at the top and bottom of the window frame and connected to said shades for operating the same, and snubber means connected to said carrier member and adapted to be connected to the window frame. 100 105 110

9. In a device of the character described, a shade carrier, means for attaching said carrier to a swingable sash, roller shades having brackets secured to opposite faces of said carrier, a combined strengthening and light intercepting head formed at one edge of the carrier in front of the shade rolls, and means for operating the shade rolls. 115

In testimony whereof I affix my signature.

WILLIAM BLANCHARD.
